ELECTRIC CIRCUIT CONTROLLING DEVICE

Emil Lange, Paris, France

Application May 11, 1948, Serial No. 26,316
In France May 16, 1947

15 Claims. (Cl. 200—150)

1

This invention relates to electric circuit controlling devices of the kind in which an arc is employed to produce a stream of quenching medium by causing a rise of pressure in a chamber containing quenching medium whilst circuit-breaking is in progress. Some forms of the device according to the invention are particularly suitable for use as circuit-breakers, and other forms are suitable for use as switches.

One object of the invention is to provide an improved electric circuit controlling device which is simple, economical in manufacture, and efficient in use.

Another object of the invention is to provide an electric circuit controlling device in which during the action of breaking the circuit there is formed an arc producing pressure in a chamber containing quenching medium, and this pressure-producing arc is extinguished by short-circuiting it or by-passing it when it has caused a sufficient rise of pressure, and the quenching medium streams out of the chamber and is used to quench the second arc.

Yet another object is to provide simple means for obturating the outlet of the quenching medium chamber until a stream of quenching medium is required to quench the newly drawn second arc.

A still further object is to provide simple means for introducing a resistance or an impedance or other current-resisting means into the circuit so as to reduce the amount of current in the second arc.

The above-mentioned objects and further objects of the invention, and the features of the invention, are to be perceived by studying the following description of devices according to the invention and the following claims in which the features of the invention are stated and claimed.

According to the first feature of the invention an electric-circuit-breaker or switch, of the kind in which an arc is employed to produce a stream of quenching medium by causing a rise of pressure in a chamber containing quenching medium, is so arranged that during the action of breaking a circuit a pressure-reducing arc is formed and this pressure-producing arc is extinguished by short-circuiting it or by-passing it when it has caused a sufficient rise of pressure in the chamber and the stream of quenching medium is used to quench a second arc. In one convenient construction the device may be so arranged that after the pressure-producing arc has been extinguished a new arc is struck by the point of a switch pin in the outlet of the pressure chamber

2

and simultaneously the outlet is freed so that the newly struck arc is extinguished by the quenching medium streaming from the pressure chamber. In a modification the pressure-producing

arc is struck in one position and a second arc to be extinguished by the quenching medium is subsequently struck in another position. In another modification a conducting element is mounted on but insulated from a movable switch pin, and whilst the circuit is closed current flows through the said conducting element. During circuit-breaking the pressure-producing arc is struck between the said conducting element and a fixed contact, and the current for the second arc flows through a resistance or the like so that the current which flows in the second arc is less than the current which flows in the pressure-producing arc. In a third modification circuit-breaking means, which form and extinguish a pressure-producing arc and a second arc, are operatively connected to a knife-switch or the like in series therewith so that during circuit-breaking the knife-switch is automatically opened after the circuit-breaking means breaks the circuit.

In the accompanying drawings five devices according to the invention are illustrated by way of example,

Figure 1 being a diagrammatic sectional view of one device,

Figure 2 a similar view of a second device provided with two sets of contacts,

Figures 3 and 4 similar views of devices provided with resistances or the like, and

Figures 5 and 6 a diagrammatic view and a detail view respectively of another device in which a knife-switch is operatively connected with circuit-breaking means.

Referring to Figure 1 of the said drawings, the device comprises a pressure chamber 1 having an outlet 4 and surrounded by a chamber 11 with which it communicates through openings 16. A switch pin 3 extends through the chamber 11 and the chamber 1 and a discharge ring 12 near the bottom of the chamber 1 to a fixed contact 2 through which it projects into the outlet 4. The lower part of the switch pin 3 comprises an insulating tube 5 in which is mounted a conducting point 13 electrically connected through resistance material 15 to the conducting body of the pin 3. In the upper part of the chamber 1 is a piston 7 loaded by a spring 8 which urges it downwards, and the space 9 above the piston 7 communicates with the chamber 11 through openings 10. The fixed contact 2 is mounted upon a metal

block 6 which is fitted with a tapered insulating tube 14 to form the outlet passage 4. The device is arranged in a circuit so that the pin 3 is electrically connected to one pole and the block 6 with the contact 2 are electrically connected to the other pole.

In circuit-breaking the device acts as follows. When circuit-breaking commences, the device is in the position shown in Figure 1 in which the pin 3 is in contact with the contact 2 and substantially closes the outlet 4. The pin 3 is moved upwards, manually or by suitable mechanical means, as rapidly as is convenient. As the body of the pin 3 withdraws from the fixed contact 2 an arc is struck between the contact 2 and the body of the pin 3 and drawn into the chamber 1, which gives rise to pressure within the chamber 1. When this pressure is sufficiently great to overcome the force of the spring 8 the piston 7 moves upwards and so the volume of the space under pressure is increased. When the insulating tube 5 is above the contact 2 the high tension current jumps the small gap between the point 13 and the contact 2 which thus come into electrical connection with each other and a second arc is formed between the point 13 and the contact 2, by-passing the first arc which is thereby extinguished. The outlet 4 is now open and the quenching medium under pressure streams out and quenches the second arc, which carries less current than the first arc owing to the resistance material 15. The quenching of the arcs is efficient because the first arc is extinguished by bypassing it and the second arc is subjected to the action of an adequate quantity of quenching medium whilst it is still newly formed and small and of reduced intensity because of the resistance material 15. The insulating tube 14 ensures that an arc is not prematurely formed between the point 13 and the block 6.

The device illustrated in Figure 2 comprises a chamber 21 divided by an apertured partition 44 and a horizontal partition 45 having apertures 25 and 26. The base of the chamber 21 is formed by a base-plate 43 to which the one pole of the electric supply is connected and which carries fixed contacts 22 and 23. In the base-plate 43 is formed an outlet 24. Above the chamber 21 is secured a guide plate 46 having slots 40 and 41 which guide the pivot pins 32 and 33 in a lever 34 pivotally secured by a pin 36 to the bottom of an electric supply member 35 which can slide up and down in a fixed annular supply contact 42. In the guide plate 46 are secured bolts 38 and 39 for determining the end positions of the lever 34. The pivot pin 32 secures a switch pin 27 to the lever 34. The pivot pin 33 is secured in the head 28 of a second switch pin comprising an insulating tube 29 filled with resistance material 31 and carrying a conducting tip 30. The pin 27, member 35, and pin 28 are connected to each other by a cable 37.

As shown in Figure 2, the device is in the current carrying position, the current path being from contact 42 through member 35, cable 37, pin 27, contact 22, and base-plate 43. In order to break the circuit the member 35 is moved upwards in any suitable manner. This withdraws the pin 27 from the contact 22 so that an arc is formed and produces pressure in a gaseous or other quenching medium in the chamber 21. As the member 35 moves further upwards the tip 30 touches the contact 23 and so the arc formed by pin 27 is by-passed, the current now flowing from member 35 through cable

31, pin head 28, resistance material 31, tip 30, and contact 23 to base-plate 43. This causes the first arc to be extinguished. As the tip 30 moves upwards from the contact 23 it forms a second arc which is of reduced strength and is immediately subjected to a stream of quenching medium passing out of the chamber 21 through the aperture 26 and outlet 24.

The device illustrated in Figure 3 comprises a mounting plate 51 on which are three pillars 52. The uppermost pillar carries a chamber 53 containing quenching medium. In the top of the chamber 53 is an annular fixed contact 55 connected to a supply terminal 56. The lower two pillars 52 carry a slotted guide plate 54 in which are fixed contacts 65 and 67. By means of terminals 66 and 68 a resistance 70 or the like is connected between the contacts 65 and 67. An insulation plate 72 is arranged behind the resistance 70. Slidably mounted in the contacts 65 and 67 is a switch pin 60, the upper part of which is reduced and surrounded by insulation 71 and a conducting tube 64. The switch pin 60 can be moved up and down by an actuating lever 59 which acts upon a trunnion 58 guided in a slot 61 in the plate 54. The poles of an electric circuit are connected to the terminals 56 and 66.

In the position shown in Figure 3 the device is in its normal current-carrying position, the current flowing from terminal 56 through contact 55, tube 64, contact 65, and terminal 66. For circuit-breaking the pin 60 carrying the tube 64 is moved downwards, and as the top edge of the tube 64 withdraws from the contact 55 it forms an arc which produces pressure within the chamber 53. When the tip of the pin 60 reaches the contact 55 the arc is by-passed and thereby extinguished, the current flowing from the contact 55 through pin 60, contact 67, terminal 68, and resistance 70 to terminal 66. As the point of the pin 60 clears the contact 55 it forms a second arc and opens the central aperture of contact 55 so that quenching medium under pressure can flow out and quench the newly formed arc.

Figure 4 shows a device generally similar to that of Figure 3, but it is inverted and the chamber 53 is filled with liquid quenching medium and is surrounded by a store chamber 78 with which it communicates by apertures 79. The chamber 78 has a terminal base plate 77 to which the fixed contact 55 is connected. The device functions in a manner similar to that of Figure 3.

Figure 5 shows a switch in which circuit-breaking means and a knife-switch for circuit-making are arranged in series with each other. The device comprises a casing 101 carrying three pillars 102, 103, and 104. The pillar 102 carries a chamber 105 having an outlet surrounded by a fixed annular contact 128 to which current is supplied through a terminal 126. The pillars 103 and 104 carry a guide plate 109 with a guide slot 108. The pillar 103 also carries a contact 127 to which is secured by a pivot 131 a knife-switch blade 120 which can engage a contact 130 carried by pillar 104 and having a supply terminal 125. A switch pin 107 may be moved up and down by an actuating lever 106, being guided in the slot 108 and the bottom of the chamber 105. The lever 106 is secured to a driving shaft 110 and is extended to carry a pivot 113 for a push rod 115. The driving shaft 110 carries a cam disc 111 with a cam lobe 112. Mounted above the driving shaft 110 is a secondary shaft

118 to which are secured arms 119, 121, and 122. The arm 121 has an abutment 134 for engagement by the push rod 115. The arm 122 is connected by a spring 114 to the pivot 113. A stop 123 is arranged to limit movement of the arm 122. Also secured to the secondary shaft 118 is a notched disc 117 which can be locked by a spring-loaded pawl 116 which is operated by the cam lobe 112. The arm 119 is connected by a link 124 to the knife-switch blade 120. An insulating tube 137 is secured near the top of the switch pin 107.

Figure 5 shows the normal current carrying position of the device. Current enters through the supply terminal 125 and passes through contact 130, blade 120, contact 127, pin 107, contact 128 and terminal 126. In order to break the circuit the driving shaft 110 is rotated manually or by any other suitable means so that the actuating lever 106 moves the pin 107 downwards. As the pin 107 moves downwards and the lower edge of the insulating tube 137 passes the lower edge of the contact 128 an arc is formed and produces pressure within the chamber 105. After some lost motion the push rod 115 engages the abutment 134 and rotates the secondary shaft 118 so that through the arm 119 and the link 124 the blade 120 is moved to the open position indicated by dotted lines, but before the knife-switch is opened by movement of the blade 120 the point of the pin 107 has passed below the contact 128 and in doing so has short-circuited the first arc and has formed a second arc which has been quenched by quenching medium flowing through the aperture of the contact 128. In this way the circuit is broken and the arc quenched before the knife-switch is opened. The position of the mechanism when the knife-switch is open is indicated in Figure 6, from which it will be seen that the disc 117 is locked by the pawl 116 so that the secondary shaft 118 cannot rotate under the action of the tension spring 114. For circuit-making the driving shaft 110 is rotated so that the lever 106 raises the pin 107. When the pin 107 has contacted the contact 128 the cam lobe 112 actuates the pawl 116 thereby releasing the shaft 118 which rotates rapidly under the action of the spring 114 so that through the arm 119 and the link 124 the knife-switch blade 120 is returned to its closed position with great speed. The mechanism thus returns to the position shown in Figure 5. From the above description it will be appreciated that the circuit is broken by the pin 107 leaving the contact 128, whereas the circuit is made by the closing of the knife-switch.

Various modifications can be introduced without departing from the invention. For example a spring-loaded piston or the like may be omitted from a device like that shown in Figure 1 or included in devices like those shown in the other figures. Instead of a resistance an impedance or other current resisting means may be used in accordance with the nature of the current for lowering the energy of the second arc. Devices according to the invention may be adapted to make use of gaseous or liquid quenching media or materials which form gases when subjected to the heat of an arc.

What I claim is:

1. An electric circuit controlling device comprising a chamber capable of containing quenching medium and having an outlet, a first fixed contact adjacent to said outlet, a movable switch pin capable of projecting through and thereby

obturing said outlet and of contacting said first fixed contact, a conducting member insulatedly mounted on said switch pin and capable of contacting said first fixed contact, a second fixed contact contacting said conducting member, a third fixed contact contacting said switch pin, and electric current resisting means connected between said second and third fixed contacts, the arrangement being such that during circuit-breaking said conducting member withdraws from said first fixed contact thereby forming a first arc producing pressure within said chamber, then said switch pin contacts said first fixed contact thereby completing a current path from said second fixed contact through said current resisting means to said third fixed contact, thence through said switch pin to said first fixed contact, then said switch pin withdraws from said first fixed contact and from said outlet thereby opening said outlet and forming a second arc in the path of quenching medium leaving said chamber through said outlet.

2. A device as claimed in claim 1, comprising also a quenching medium container in communication with and capable of supplying quenching medium to and receiving quenching medium from said chamber.

3. An electric circuit controlling device comprising in combination a quenching medium receptacle having an outlet, a fixed contact adjacent to said outlet, a partly insulated movable switch pin capable of projecting through and thereby obturating said outlet and of contacting said fixed contact, an actuating lever connected to and capable of actuating said switch pin, a driving shaft carrying said actuating lever, and knife-switch means in series with said switch pin and operatively connected with said driving shaft, the arrangement being such that during circuit-breaking said switch pin draws from said fixed contact a first arc producing pressure within said receptacle, said switch pin then contacts said fixed contact thereby bypassing said first arc, said switch pin then withdraws from said fixed contact and from said receptacle outlet thereby drawing a second arc in the path of quenching medium leaving said receptacle, said second arc is quenched, and said knife switch means is then opened.

4. A device as claimed in claim 3, the arrangement being such that during circuit-making said switch pin returns to a current-carrying position and thereafter said knife-switch means is closed.

5. A device as claimed in claim 3, comprising a secondary shaft mounted for control by said driving shaft, a push-rod capable of transmitting motion in one direction to said secondary shaft from said driving shaft and of permitting motion of said driving shaft in opposite direction without moving said secondary shaft, a detent mechanism operated by said driving shaft and capable of holding said secondary shaft in a position of rest, and resilient means acting on said secondary shaft and tending to move said secondary shaft in a direction opposite to that of the motion transmitted to said secondary shaft by said push-rod.

6. An electric circuit-breaker comprising a quenching-medium receptacle having an outlet, a stationary contact member adjacent to said outlet, a movable contact member partly of insulating material and capable of entering and thereby obturating said outlet and of sliding in contact with said stationary contact member, all in combination whereby during circuit-breaking

said movable contact member whilst obturating said outlet draws a first arc producing pressure within said receptacle, then comes into electrical connection with said stationary contact member and thereby by-passes said first arc, then withdraws from said outlet and said stationary contact thereby drawing a second arc in the path of quenching medium leaving said receptacle through said outlet.

7. An electric circuit-breaker comprising a quenching-medium receptacle having an outlet, a stationary contact close to said outlet, a movable contact consisting of a conducting body and a conducting tip secured by insulation to said body and electrically connected through resistance material to said body, a loaded piston within said receptacle and dividing said receptacle into two compartments, and a quenching medium storage vessel in communication with both of said compartments, said movable contact moving during circuit-breaking to form between said body and said stationary contact a first arc producing pressure in said receptacle between said piston and said outlet and to by-pass said first arc by forming a second arc between said tip and said stationary contact and in the path of quenching medium leaving said receptacle through said outlet.

8. An electric switch comprising a quenching-medium receptacle having an outlet, a stationary contact at said outlet, and a movable contact which can pass partly through and thereby obstruct said outlet and can slide in contact with and withdraw from said stationary contact and can withdraw from said outlet, and an insulating shield on said movable contact whereby electrical contact between said movable contact and said stationary contact is interrupted during part of the movement of said movable contact whereby as said movable contact moves during circuit-breaking a first arc producing pressure in said receptacle is drawn between said movable contact and said stationary contact while said movable contact obstructs said outlet, and later said first arc is by-passed when said movable contact comes into electrical connection with said stationary contact, and still later said movable contact withdraws from said stationary contact and said outlet whereby said outlet is cleared and a second arc is drawn out in the path of quenching medium leaving said receptacle through said outlet.

9. In an electric circuit controlling device the combination comprising a quenching-medium receptacle having an outlet, a substantially annular stationary contact defining part of the path of quenching medium passing out through said outlet, and a movable contact member capable of obstructing said outlet and contacting said stationary contact and of drawing from said stationary contact during circuit-breaking an arc producing pressure in said receptacle and of bypassing said arc by coming into electrical connection with said stationary contact and of clearing said outlet and drawing from said stationary contact a second arc in the path of quenching medium passing out through said outlet.

10. An electric circuit controlling device comprising in combination a chamber capable of containing quenching medium and having an outlet, means for forming during circuit-breaking a first arc producing pressure within said chamber, at least one fixed contact, at least one movable conductor capable of coming into electrical connection with said fixed contact and thereby bypassing and so extinguishing said first arc after

it has produced pressure within said chamber, and circuit-breaking means forming after the by-passing of said first arc a second arc in the path of quenching medium passing out of said chamber through said outlet.

5 11. An electric circuit controlling device comprising in combination a chamber capable of containing quenching medium and having an outlet, a fixed contact adjacent to said outlet, a movable compound pin capable of projecting through said outlet, means in mechanical connection with said movable compound pin for forming during circuit breaking a first arc producing pressure within said chamber, said compound pin having a conducting portion which comes into electrical connection with said fixed contact and thereby bypasses said first arc after it has produced pressure within said chamber and then withdraws from said fixed contact drawing out a second arc in 15 the path of quenching medium passing out of said chamber through said outlet.

20 12. An electric circuit controlling device comprising in combination a chamber capable of containing quenching medium and having an outlet, 25 a fixed contact adjacent to said outlet, a movable compound pin capable of projecting through said outlet, separable contactors drawing out during circuit breaking a first arc which produces pressure within said chamber, an insulating sleeve 30 on said compound pin permitting said compound pin to make an initial movement without coming into electrical connection with said fixed contact, and a conducting tip on said compound pin which comes into electrical connection with said fixed 35 contact and thereby bypasses said first arc after it has produced pressure within said chamber and then withdraws from said fixed contact drawing out a second arc in the path of quenching medium passing out of said chamber through said 40 outlet.

13. An electric circuit controlling device comprising a chamber capable of containing quenching medium and having an outlet, a first fixed contact within said chamber, a first switch pin 45 having an end movable within said chamber and capable of contacting and withdrawing from said first fixed contact, a second fixed contact adjacent to said outlet, a second switch pin capable of contacting and withdrawing from said second 50 fixed contact, said second switch pin consisting of a body, an insulating sleeve secured to said body, a switch pin point mounted in said sleeve, and resistance material electrically connecting said point to said body, mechanical means connected to and co-ordinating movements of said switch pins, and circuit means connected to said switch pins and contacts, the arrangement being such that during circuit-breaking said first switch pin forms a first arc producing pressure within 55 said chamber, then said point of said second switch pin comes into electrical connection with said second fixed contact thereby bypassing said first arc, and then said switch pin point withdraws from said second fixed contact thereby 60 forming a second arc in series with said resistance material in the path of quenching medium leaving said chamber through said outlet.

14. An electric circuit controlling device comprising in combination a chamber capable of containing quenching medium and having an outlet, 70 a fixed contact adjacent to said outlet, a movable compound pin capable of projecting through said outlet, separable contactors drawing out during circuit breaking a first arc which produces pressure within said chamber, an insulating sleeve

on said compound pin permitting said compound pin to make an initial movement without coming into electrical connection with said fixed contact, and a conducting tip on said compound pin which comes into electrical connection with said fixed contact and thereby by-passes said first arc after it has produced pressure within said chamber and then withdraws from said fixed contact drawing out a second arc in the path of quenching medium passing out of said chamber through said outlet, and switch means in series with said compound pin and operatively connected with said compound pin whereby said switch means is automatically opened after said compound pin has operated for breaking a circuit.

15. An electric circuit controlling device as

claimed in claim 14, said movable compound pin and said switch means being so operatively connected that said switch means is automatically closed after said movable compound pin has re-turned to a current-carrying position.
